UNITED STATES PATENT OFFICE

120,515

DESIGN FOR A SHOE

John Roman, Winchester, Mass., assignor to
Trimmings, Inc., Lawrence, Mass., a corpora-
tion of Massachusetts

Application February 28, 1940, Serial No. 90,583

Term of patent 3½ years

To all whom it may concern:

Be it known that I, John Roman, a citizen of the United States, residing at Winchester, in the county of Middlesex and Commonwealth of Massachusetts, have invented a new, original, and ornamental Design for Shoes, of which the following is a specification, reference being had to the accompanying drawing, forming part thereof.

In the drawing,

Fig. 1 is a top plan view of a shoe showing my new design; and

Fig. 2 is a view in side elevation of the shoe.

The dominant feature of my design resides in the ornamental vamp and toe strap assembly wherein the strap extends through openings in the vamp to simulate a decorative knot above the instep of the shoe and portions of the strap cross one another forwardly of said openings and extend diagonally to the opposite lateral edges of the toe portion of the shoe bottom.

I claim:

The ornamental design for a shoe, substan-
tially as shown and described.

JOHN ROMAN.
